Inventor:

UNITED STATES PATENT OFFICE.

BURNHAM C. STICKNEY, OF ELIZABETH, NEW JERSEY, ASSIGNOR TO UNDERWOOD TYPEWRITER COMPANY, OF NEW YORK, N. Y., A CORPORATION OF DELAWARE.

TYPEWRITING MACHINE.

Application filed November 5, 1921. Serial No. 513,001.

To all whom it may concern:

Be it known that I, BURNHAM C. STICKNEY, a citizen of the United States, residing in Elizabeth, in the county of Union and State of New Jersey, have invented certain new and useful Improvements in Typewriting Machines, of which the following is a specification.

The present invention relates to sound-deadening casings for typewriting machines and more particularly to the window thereof through which the printing is visible to the operator.

It has been found that artificial light or sunlight, striking the window or window-pane at certain angles, is objectionably reflected into the eyes of the operator. To divert such objectionable reflection of light, recourse has been had to angular adjustment, forward and backward, of the window-pane in its frame. Such adjustment in one plane, within the limits prescribed by the casing structure, may not always be sufficient; or, to be sufficient, might require a window-frame of otherwise undesirable dimensions.

An object of the present invention is the provision of means whereby the window-pane may be adjustable universally; that is to say, laterally as well as forward and rearward, to any angle required for satisfactory diversion of the reflected light.

In attaining this object of the invention, and in the preferred embodiment thereof, the window-pane is mounted, for angular adjustment in one plane, in a frame which is itself mounted for angular adjustment, in the wall of the casing, in another plane, preferably at right angles to the plane of the first adjustment.

Another object of the invention is the provision of means for effecting a lateral, as contradistinguished from a forward and rearward, angular, movement of the window-pane, whether or not accompanied by means for effecting such forward and rearward angular adjustment.

Other features of the invention relate to the means by which one frame is pivotally mounted in the other, and to means for providing sound-deadening joints between the two frames and between the pane and the frame in which it is immediately mounted;

and to means for releasably holding the adjustable frame and pane at any angle to which the same may be set.

Other features and advantages will hereinafter appear.

In the accompanying drawings,

Figure 1 is a side view, in cross-section, of the upper part of the casing with the machine shown therein.

Figure 2 is a top plan view of the casing.

Figure 3 is a view, in cross-section, taken on the line 3—3 of Figure 2.

Referring to the drawings, the casing-body 10 is shown as having a cover 11 hinged thereto at 12. On the main frame 13 of the typewriting machine within the casing, the carriage 14 has letter-feed and return movements on a rear rail 15 and a front rail (not shown). The platen 16 is mounted for rotary movement in a platens-frame 17 on the carriage. The line-space lever 18, 20, is pivoted to the carriage at 19.

The casting forming the cover-portion of the casing is shown as having a rectangular ribbing 27 which re-enforces the same and serves as a frame for a window-pane 28. The ribbing 27 is of considerable depth and provides a flange 29 on the outside of the cover and a flange 30 on the inside of the cover. The interior flange 30 serves as an abutment for the sound-deadening lining 31.

A second window-frame or sash 32, conforming to the shape of the frame 27, is set snugly within the latter, and has ears 33 (see Figure 3) by means of which it is pivoted to the frame 27. Screws 34, passing through the ears 33 and into lugs 35 of the ribbing 27, serve as pivot-pins for the sash or frame 32. It is to be noted that in Figure 1 the abutting sides of the frames 32 and 27 are straight; whereas, as shown in Figure 3, the abutting ends of the frames 32 and 27 are curved on arcs struck from the pivots 34. Strips 36 of felt, leather or other sound-proof material, are preferably attached to the interior end faces of the frame 27 to make the joints sound-proof at these places. These strips 36, against which the ends of the frame 32 press, also have the function of holding the frame 32 in any angular adjustment thereof. Upon loosening the screws 34, the frame 32 may be adjusted

to any desired angle, whereupon the screws 34 are tightened to hold or to assist in holding the frame 32 in adjusted position.

Pivotaly mounted on the interior faces 5 of the end cross-pieces of the frame 32 are brackets 37. Screws 38, passing through the brackets 37 and into lugs 39 on the end cross-pieces of the frame 32, serve as pivot-pins for the brackets. The window or window-pane 28, of glass or other transparent material, is supported upon the brackets 37, and is secured thereto by screws or rivets 41, which pass through the pane and into the platforms 43 of the brackets. As shown in 10 Figure 1, the inner faces of the front and rear cross-pieces of the frame 32 are curved on an arc struck from the pivots 38, and are also preferably lined with strips 44 of felt or leather, or other yieldable sound-deadening material, to render sound-proof the joints formed by the front and rear edges of the window-pane and the front and rear cross-pieces of the frame 32. The front and rear edges of the pane 28 are shown as 15 rounded so that, when the window-pane is swung on its pivots 38, the edges thereof may move over the strips 44 without jamming or tearing the latter. Upon loosening the screws 38, the pane may be tipped forward or backward to any desired angle; after which the screws 38 are tightened to assist the strips 44 in holding the pane in 20 adjusted position.

It will thus be seen that the pane may be 25 tilted forward or backward to any desired adjusted position of the frame 32, and that the frame 32 itself may be tilted laterally to any desired angular adjustment of the frame 27. The frames are of a depth sufficient to permit of considerable amplitude 30 of adjustment.

Certain features herein disclosed are made 35 the subject-matter of the application of John Waldheim, Serial No. 512,741, filed 40 November 4, 1921; but none of the claims herein could be made in said Waldheim application. This invention is in the nature of 45 an improvement upon the structure shown in said application and in the patent granted to said John Waldheim, July 1, 1924, No. 1,499,709. Said Waldheim inventions are in the nature of improvements upon the machine covered by an application Serial No. 381,259, filed by me May 14, 1920. The 50 present case contains no claim that could be made in said application No. 381,259.

Variations may be resorted to within the 55 scope of the invention, and portions of the improvements may be used without others.

Having thus described my invention, I claim:

1. A sound-deadening typewriter-casing having an observation-window-pane to afford a view of the work in the machine, said 60 window-pane being pivoted for universal

adjustment in an opening in the casing to avoid objectionable reflection of light from said window-pane, and means for maintaining a sound-proof seal between the edges of the opening and said window-pane irrespective of such adjustment. 70

2. A sound-deadening typewriter-casing having a work-viewing window-pane tiltable endwise of the casing in an opening therein to avoid objectionable reflection of light from the window-pane, and means for maintaining a sound-deadening seal between the edges of such opening and said window-pane irrespective of the tilting position of said window-pane. 75

3. A sound-deadening typewriter-casing having a fixed work-viewing frame, a second frame pivoted at the front and rear in the first frame, a window in the second frame tiltable laterally therewith to avoid objectionable reflection of light, and means for maintaining a sound-deadening seal between the first and second frames irrespective of the adjusted position of the latter. 80

4. A sound-deadening typewriter-casing having a fixed work-viewing frame, a second frame pivoted at the front and rear in the first frame, a window pivoted at the right and left in the second frame and tiltable laterally with the second frame and forwardly and rearwardly in the second frame for universal adjustment to avoid objectionable reflection of light, means for maintaining a sound-proof seal between the window and the second frame, and means for maintaining a sound-proof seal between the second frame and the first frame. 90

5. A sound-deadening typewriter-casing having a fixed work-viewing frame, a second frame pivoted at opposite points in the first frame, brackets pivoted at opposite points in the second frame to swing about an axis perpendicular to the pivotal axis of the second frame, a window secured to said brackets and universally adjustable about said axes to positions to avoid objectionable reflection of light, means for maintaining a sound-proof seal between the window and the second frame, and means to maintain a sound-proof seal between the second frame and the first frame. 105

6. A sound-deadening typewriter-casing having a fixed rectangular work-viewing frame, a second frame pivoted in the first frame at the middle points of two opposite edges thereof, ears projecting inwardly from the middle points of the other two edges thereof, a window in said second frame, brackets extending inwardly from said window adjacent said ears, screws for pivotally connecting said brackets and said frames to permit angular adjustment of the window in the second frame and for holding the window in adjusted position when the screws are tightened, said window being 110

tiltable in two directions to avoid objectionable reflection of light, means for maintaining a sound-proof seal between the window and the second frame, and means to 5 maintain a sound-proof seal between the second frame and the first frame.

7. In a sound-deadening casing for a type-writing machine, a work-viewing window-frame, a window pivotally mounted in the 10 frame for adjustment to avoid objectionable reflection of light, the faces of the frame being curved on an arc struck from the pivotal axis to permit a close fit of the window in the frame irrespective of its adjustment 15 therein, and means for maintaining a sound-proof seal between the window and the frame.

8. In a sound-deadening casing for a type-writing machine, a fixed work-viewing window-frame in the wall thereof, a second window-frame pivotally mounted in the fixed frame, a window in the second frame, the opposing faces of the two frames being curved on arcs struck from the axis of the 25 pivot, and means for maintaining a sound-proof seal between said frames irrespective of the adjustment of the second frame to avoid objectionable reflection of light from said window.

9. In a sound-deadening casing for a type-writing machine, a fixed work-viewing window-frame in the wall thereof, a second frame pivotally mounted in the fixed frame, a transparent window in the second frame, and adjustable therewith to different positions to avoid objectionable reflection of 35 light, and means, including a strip of yieldable sound-deadening material binding one of said frames, to maintain a sound-proof 40 joint between the frames, irrespective of the adjusted position of the second frame.

10. In a sound-deadening casing for a type-writing machine, a fixed observation-window-frame in the wall thereof, a second

frame pivotally mounted in the fixed frame, 45 a transparent window in the second frame and adjustable therewith to different positions to avoid objectionable reflection of light, and means, including a strip of yieldable material binding one of said frames for 50 contact of the other frame therewith, to maintain a sound-proof seal between the frames and to assist in holding the second frame in adjusted position.

11. A sound-deadening casing for a type-writing machine, having a work-viewing opening in one wall thereof, a window in said opening, and means for providing universal angular adjustment of the window in the opening to avoid objectionable reflection 60 of light, and for maintaining a sound-proof seal between the window and the sides of the opening.

12. A sound-deadening casing for a type-writing machine, having a work-viewing 65 opening in one wall thereof, a window in said opening, means for providing universal angular adjustment of the window in the opening to avoid objectionable reflection of light, and means for rendering sound- 70 proof the joints between the window and its frame in any angular adjustment of the window.

13. A sound-deadening casing for a type-writing machine, having a work-viewing 75 opening in one wall thereof, a window in said opening, means for providing universal angular adjustment of the window in the opening to avoid objectionable reflection of light, and for maintaining a sound-proof 80 seal between the window and the sides of said opening, and means for holding the window in any adjusted position of the same.

BURNHAM C. STICKNEY.
